UNITED STATES PATENT OFFICE

BENJAMIN H. MARCUS, OF BROOKLYN, NEW YORK

BUCKLE-PURSE

Application filed February 12, 1930, Serial No. 427,671. Renewed June 8, 1932.

This invention relates to purses adapted to be attached to belts and the like, and has for one of its objects the provision of a purse of this nature that is water tight and can readily be used as a bathing belt buckle or as a buckle for other belts or the like.

Another object of the invention is to provide a purse of this nature with a cover or lid that can readily be removed or inserted 10 into the body or base portion of the purse and maintained therein in water tight condition.

Another object is to produce a device of the character described in which the maximum simplicity of construction and operation 15 is secured.

Other objects and advantages will appear as the nature of the improvements is better understood, the invention consisting substantially in the novel arrangement and co-relation of parts herein fully described, and illustrated in the accompanying drawing, wherein similar reference characters are used to describe corresponding parts throughout the several views, and then finally pointed out and specifically defined and indicated in the appended claims.

The disclosure made the basis of exemplifying the present inventive concept suggests 30 a practical embodiment thereof, but the invention is not to be restricted to the exact details of this disclosure, and the latter, therefore, is to be understood from an illustrative, rather than a restrictive stand-point.

The inventive idea involved is capable of receiving a variety of mechanical expressions, one of which, for the purpose of illustration, is shown in the accompanying drawing, in which

Figure 1 is a top plan view of my improved belt purse.

Figure 2 is a sectional view thereof taken on line 2-2 Figure 1.

Figure 3 is a sectional view taken on line 3-3 Figure 1.

Figure 4 is a perspective view of the purse base.

Figure 5 is a perspective view of the purse cover or lid with a portion thereof broken

away for the sake of clearness, and Figure 6 is a fragmental perspective view partly in section of a modified form of my invention.

Referring now to the drawing in detail 10 indicates the body or base portion of my improved purse, the said base being provided with a centrally located downwardly tapering recessed chamber or depression 11 having a bottom wall 12, side walls 13 and 14 and end walls 15 and 16, the side wall 14 being provided with a bead or groove 17 near the top thereof and which may run the entire length of the recess 11.

The groove 17 is adapted to receive therein a rounded end 20 of an extension 21 on a lid or cover 22. The lid or cover 22 is in the form of a casing open at the bottom end thereof around which opening there extends a flange 23. A similar flange 24 but somewhat wider than the flange 23 extends all around the top wall 25 of the said lid 22. The said flange 24 is adapted to rest on the top of the base 10 to close the depression 11 therein. A tapered rubber gasket 26 surrounds the lid 22 between the flanges 23 and 24 to make the purse water tight when closed.

To releasably close the purse, I provide a latch 30 which extends through an opening 31 in the base 10 and is slidably maintained on an extension 32 bent up from the said base. A cam lever 33 pivoted at 34 maintains the lid in closed position against the tension of a leaf spring 35 secured to the latch 30 and bearing against the wall 13 of the base 10.

To open the purse the lever 33 is swung up and to the left from its Figure 1 position and the spring 35 will slide the latch 30 out of engagement with the flange 24 of the lid 22 thus permitting the said lid to be lifted out of the recess 11.

One end of a belt 37 is passed through a slot or opening 38 in the base 10, and suitably secured to the base, and the other end of the belt is free to pass through a slot 39 at the opposite end of the base 10 and adapted to be secured around the waist of a wearer by any suitable clasp or other fastening means.

In Figure 6 I have shown a modified form of my invention, wherein I show a hook or groove forming portion 40 on the base 10, in-

stead of the groove 17 to accommodate the rear end of the top flange 24 to normally maintain the lid in place on the base 10.

From the foregoing it will be seen that I have provided water tight belt buckle purse, simple in construction and efficient in action.

Having described my invention what I claim as new and desire to secure by Letters Patent is:

- 10 1. In a purse adapted to be attached to a belt, a base, a chamber, tapering side and end walls in the chamber, one of the said walls being provided with a groove, a lid, a flanged top on the said lid adapted to rest on the base, side and end walls depending from the said top, a flange on the bottom of the said walls, a gasket supported between the top and bottom flange, an extension on the lid adapted to be received by the groove, and means for releasably maintaining the lid in closed position on the base.
- 15 2. In a purse adapted to be attached to a belt, a base, a chamber, tapering side and end walls in the chamber, one of the said walls being provided with a groove, a lid, a flanged top on the said lid adapted to rest on the base, side and end walls depending from the said top, a flange on the bottom of the said walls, a gasket supported between the top and bottom flange, an extension on the lid adapted to be received by the groove, a spring pressed latch supported on the base for engagement with the lid, and a cam lever in engagement with the latch for the purpose specified.
- 20 3. In a purse of the nature described, a base, a chamber provided with a groove therein, a lid overlying the said chamber, walls depending from the lid and extending into the chamber, an extension on the lid adapted to fit into the groove, a spring actuated latch for engagement with the lid, means in engagement with the latch for maintaining the said latch in engagement with the lid, and a gasket encircling the depending lid walls and engaging the walls of the chamber to make same water tight.
- 25 4. In a purse adapted to be attached to a belt, a base, a chamber therein provided with a groove, a lid extending into the chamber, flanges at the top and bottom of said lid, a gasket between said flanges, and a projection on the lid adapted to be received by the groove.
- 30 5. In a purse adapted to be attached to a belt, a base, a chamber therein provided with a groove, a lid extending into the chamber, flanges at the top and bottom of said lid, a gasket between said flanges, a projection on the lid adapted to be received by the groove, and means for releasably maintaining the lid in closed position on the base.

In testimony whereof I hereunto affix my signature.

BENJAMIN H. MARCUS.
